United States Patent

Des. 235,968

Patented July 22, 1975

235,968

NAIL DRIVING DEVICE

Edward G. Mein, 6672 Sims Drive,
Oakland, Calif. 94611

Filed Jan. 28, 1974, Ser. No. 436,932

Term of patent 14 years

Int. Cl. D8—02

U.S. Cl. D8—75

FIG.—1

FIG.—2

FIG.—3

FIG.—4

FIG.—5

FIG. 1 is a perspective view of a nail driving device showing my new design;

FIG. 2 is a side elevational view thereof;

FIG. 3 is a side elevational view similar to FIG. 2, but having the central rod and attached weighted end portion partially withdrawn from the rod guide section thereof;

FIG. 4 is a front view thereof; and

FIG. 5 is a rear view thereof.

I claim:

The ornamental design for a nail driving device, as shown and described.
